1,010,659. FLOOR-PLATE. FRANK E. McCABE and MORTIMER C. ROSENFIELD, Cleveland, Ohio; said McCabe assignor to The Grabler Manufacturing Company, Cleveland, Ohio, a Corporation of Ohio. Filed Mar. 9, 1910. Serial No. 548,244.

To all whom it may concern:

Be it known that we, FRANK E. McCABE and MORTIMER C. ROSENFIELD, citizens of the United States, residents of Cleveland, county of Cuyahoga, and State of Ohio, respectively, have invented a new and useful Improvement in Floor-Plates, of which the following is a specification, the principle of the invention being herein explained and the best mode in which we have contemplated applying that principle, so as to distinguish it from other inventions.

Our invention relates to floor or ceiling plates for covering apertures through which pass pipes or the like, the object of said invention being to provide such a floor plate which may be secured in place after the pipe has been placed in position, and which will present a smooth and finished exterior appearance.

The said invention consists of means hereinafter fully described and particularly pointed out in the claims.

The annexed drawing and the following description set forth in detail certain means embodying our invention, the disclosed means, however, constituting but one of various mechanical forms in which the principle of our invention may be applied.

In said annexed drawings: Figure 1 is a perspective of a section of a pipe passing through a floor, and showing one of our improved plates in position thereon. Fig. 2 is a bottom plan of a floor plate embodying our invention, the parts thereof being shown in their normal or closed position. Fig. 3 is a bottom plan of said floor plate showing the parts in a detached and partially open position. Fig. 4 is a bottom plan of a floor plate showing the parts in their open position.

Our invention as illustrated consists of two semi-annular members A and B preferably struck up of sheet metal so as to form a marginal flange a on the plate. The interior circular opening b is made of a diameter such as will permit the plate to be fitted closely around the particular size of pipe to which it is to be applied. To the under side of that portion of each of the members adjacent to the contiguous edges a' and b' of the members A and B respectively, is secured a hinge C, the latter being placed intermediately of the two inner and outer edges a^2 and b^2 of the plate. This hinge has two pivotal axes a^3 and b^3 which intersect the plate perpendicularly and which are located in two different parallel planes perpendicular to the edges a' and b' when in their normal or contiguous position. This construction gives the hinge two axes of oscillation, so that the two parts may be moved into the

position shown in Fig. 3, the hinge oscillating about the axes a^3 and b^3 . By now turning the member A about the axis b^3 and simultaneously turning it about the axis a^3 , the two parts may be separated to assume the position shown in Fig. 4, in which position it may be placed about the pipe and closed thereon. The outer swinging end of the member A is provided with a fixed fastening member a^4 which projects beyond the outer end of this member, such projecting portion being formed with an aperture a^5 . The free or swinging end of the member B is formed with a struck-up projection b^4 , which is adapted to engage the aperture a^5 , there being sufficient spring in the device to permit such engagement, or after such engagement to permit disconnection of member a^4 from the projection b^4 .

In order to hold the plate in place snugly around the pipe, a yielding spring D is secured to one of the members and projects into the interior opening b , a portion b^6 of the metal being struck up so as to form a projection to which the spring D may be secured. One of the members is provided with a struck-up projection a^6 on its under side, which may be driven into the floor or ceiling and so prevent turning of the plate on the pipe.

Having fully described our invention, what we claim and desire to secure by Letters Patent is:

1. A floor plate comprising the combination with two surrounding members having two normally contiguous extremities when in their closed position; of a hinge having an axis on each of said members and adjacent to said extremities; said axes being perpendicular to the plane of movement of said members, and located in two different planes perpendicular to the line of contiguity of said extremities.

2. A floor plate comprising the combination of two flat semi-annular members having two normally contiguous extremities; a hinge joining that part of said members adjacent to said extremities, and having an axis of oscillation on each of same perpendicular to the plane of movement thereof; said axes furthermore being located in two different planes perpendicular to the line of contiguity of said extremities.

Signed by us, this 8th day of March, 1910.

FRANK E. McCABE.

MORTIMER C. ROSENFIELD.
